RUG.

No. 17,087.

Patented Feb. 8, 1887

UNITED STATES PATENT OFFICE.

GEORGE B. FOX, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 17,087, dated February 8, 1887.

Application filed January 10, 1887. Serial No. 223,936. Term of patent 3½ years.

To all whom it may concern:

Be it known that I, GEORGE B. FOX, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in the representation of two cats. One is represented as lying down, the other sitting down on a rug. The background shows steps. The ends and upper corners are ornamented by masses of floral ornamentations, as shown.

What I claim as my invention is—

The design for a rug, consisting of the representation of two cats on a rug, a background representing steps, and the ends and upper corners ornamented, as shown.

GEO. B. FOX.
